FOLDABLE STADIUM SEAT

Claude W. Ahrens, W. Highway 6,
Grinnell, Iowa 50112

Filed Apr. 16, 1971, Ser. No. 134,914

Term of patent 14 years

Int. Cl. D6—02

U.S. Cl. D6—41

FIG. 1

FIG. 2

FIG. 3

FIG. 5

FIG. 4

FIG. 6FIG. 7FIG. 1 is a rear perspective view of the foldable stadium seat showing my new design;

FIG. 2 is a side elevational view;

FIG. 3 is a top view;

FIG. 4 is a bottom view;

FIG. 5 is a front elevational view;

FIG. 6 is a rear perspective view of the foldable stadium seat wherein a horizontal mounting foot has been substituted for the upright mounting foot; and

FIG. 7 is a side elevational view of the foldable stadium seat shown in FIG. 6.

I claim:

The ornamental design for a foldable stadium seat, substantially as shown.
